(57) **CLAIM**

The ornamental design for a dentifrice, as shown and described.

DESCRIPTION

The dentifrice is shown as dispensed in two segments, one segment substantially transparent containing thin quadrangular shaped pieces and the other segment being primarily opaque.

FIG. 1 is a perspective view of the dentifrice of my design; FIG. 2 is a right side elevation thereof.

FIG. 3 is a front elevation view thereof.

FIG. 4 is a left side elevation view thereof.

FIG. 5 is a perspective view of an additional embodiment thereof.

FIG. 6 is a right side elevation view thereof.

FIG. 7 is a front elevation view thereof; and,

FIG. 8 is a left side elevation view thereof.

The broken line showing of a toothbrush and a tube are for illustrative purposes only and form no part of the claimed design.
